E. CURTI

PNEUMATIC HAMMER

Filed July 30, 1920

FIG. 1.

Fig. 3.

Inventor
F. Curti

Attorney

UNITED STATES PATENT OFFICE.

ERNESTO CURTI, OF MILAN, ITALY.

PNEUMATIC HAMMER.

Application filed July 30, 1920. Serial No. 400,225.

To all whom it may concern:

Be it known that I, ERNESTO CURTI, a subject of the King of Italy, residing at Milan, in the Kingdom of Italy, have invented certain new and useful Improvements in Pneumatic Hammers, of which the following is a specification.

This invention relates to pneumatic hammers of the type actuated by a single piston 10 compressor, and in which a single pipe connects the compressor to the hammer.

In the annexed drawing two alternative embodiments of a single piston compressor actuated hammer are shown.

15 Referring to the drawing:

Figure 1 is a sectional elevation of one form of hammer.

Fig. 2 is a cross section of the guiding stem for the auxiliary piston of the hammer.

Fig. 3 is a vertical sectional view of a modification.

The single piston compressor used in connection with the invention is not illustrated 25 in the drawing but is of the common construction, such as is disclosed by my previous Italian Patent No. 172,720, and is provided with a single piston traveling to and fro within a single cylinder. Only one valve 30 is used and a single air pipe only extends from the compressor to the hammer. In case two or more compressors are grouped for the sake of compactness of the working system of tools, or for the sake of an easier 35 control from a single motor, each compressor controls a hammer, the hammers being as many as the grouped compressors.

The hammer according to the embodiment shown in Fig. 1 comprises a cylinder 1 40 having a bore in which the hammer piston 2 reciprocates. A hollow trunk-shaped stop 3 serves to limit the stroke of the reciprocating hammer piston at the outer end of its stroke. 4 is the air pipe from the compressor which opens into the bore of the cylinder 1 at the upper end thereof, and adjacent to the cone-shaped stop 3. The stem of the tool 5 projects into the bore of the cylinder 1 to receive the blows struck by 45 the hammer piston 2.

At one side of the cylinder 1, and integral therewith, another cylinder 6 is provided, wherein an auxiliary piston 7 reciprocates.

A stem 8 extends therefrom and projects into a cylindrical guide sleeve 9. The stem 55 8 has helical grooves 10 on its surface, which engage similar teeth on the hub of a pinion 11. A plate 12 secures the pinion 11 in place and said pinion is capable of rotating, but is prevented from any axial displacement by said plate. Pinion 11 meshes by means of an intermediate idle pinion 13, with a gear 14, whereby the rotary motion of pinion 11 is transmitted to gear 14, which is incapable of a displacement along 60 the axis of cylinder 1, but can freely rotate about this axis. By means of a key or the like, the stem of the tool 5 is fixed to rotate with the gear 14 and is capable of axial movement relatively to said gear. 70

One of the toothed wheels is associated with a device which permits of the rotation taking place in only one direction. This device consists of a toothed disk fixed to the gear 11 and cooperating with a pawl diagrammatically shown at 11'. Between the outer face of the auxiliary piston 7 and the head of the cylinder 6 a spring 15 is fitted for aiding in moving the piston 7 in one direction. The cylinder 6 has, near its head, a 80 hole 17 to the atmosphere, and a port 16 places the lower portions of cylinders 1 and 6 in communication. The tool 5 and its stem are bored axially, and the extension 8 and the piston 7 are also provided with an axial bore. 85

The hammer operates as follows:

Assuming the hammer 2 to be at the upper end of its stroke, air pressure from pipe 4 is injected into the cylinder 1 and this forces 90 the hammer 2 downwardly against the tool stem. While lowering, the hammer compresses the air within the lower space of cylinder 1, and, owing to the port 16, this air passes into the lower space of the cylinder 6, and the auxiliary piston 7. As the piston 7 rises it compresses the spring 15. As soon as the supply of pressure air from 4 ceases, and the suction exerted from the cylinder of the compressor commences, a depression takes place above the hammer 2 and the latter quickly makes its upward stroke, not only because of this depression, but due to the stored air pressure within cylinder 6, assisted also by the spring 15 which is expanding during the upward stroke of the 100 105

hammer 2. The momentum of piston 7 at the end of its downward stroke maintains within the lower space of cylinder 6 the air pressure which assists the hammer while 5 rising. For the purpose of maintaining within the lower spaces of cylinders 1 and 6, the required quantity of air, the hammer 2 uncovers before reaching its upper position, a port 18 which through the bore of 10 cylinder 6 and port 17 establishes a communication between the atmosphere and the inner lower spaces of cylinders 1 and 6.

Piston 7 reciprocates within the cylinder 6 in synchronism with the hammer 2. Owing 15 to the helical grooves of the extension 8 and to the dog 11 mentioned above, as the piston 7 moves in one direction the toothed wheels 11 and 14 will be rotated thereby, whilst as the piston 17 moves in the opposite direction, the toothed wheels will not rotate, and to the piston 7 a rotary motion 20 will be imparted. Owing to the momentum of the piston 7, the resistance offered by the toothed wheels, will be overcome so that a 25 rotary motion of the piston, when the toothed wheels are rotated, will not take place. The axial bore of the stem 8 is provided to permit air to enter and be discharged from the chamber 9.

30 The axial bore of the tool 5 and its stem permits a jet of air from cylinder 1 to be projected from the outer end of the tool, to clean the surface operated upon by the latter, and to prevent dust from entering the 35 inner chambers of the machine.

By the improved construction the tool is pushed against the surface to be worked and at the same time is rotated about its axis.

40 If it is desired to utilize the compression from the compressor for raising the hammer piston, the suction from the compressor may be used to lower the hammer, and the hammer can be constructed as shown in Fig. 3. 45 In this modification 19 is the cylinder, 20 the hammer proper, 23 the tool, 21 (at the lower end of the cylinder) the pipe from the compressor, 22 (at the upper end of the cylinder) the pipe to the auxiliary cylinder 6 as 50 in Fig. 1. In this construction the tool is not rotated and consequently the rotating means are dispensed with.

The hammer 20 is forced upwardly by the pressure introduced below it from the compressor, and while rising, air pressure will 55 be forced through pipe 22 into the cylinder 6, and the spring 15 will be compressed. As the hammer 20 reaches its upper position, a depression is created below the same by the 60 compressor; and this will assist the descent of the hammer 20 which is also pushed by the air pressure from cylinder 6 entering through pipe 22.

During the downward stroke of the piston 65 20, the suction from 21 exerted within the

cylinder 19 will raise the tool upwardly in the cylinder.

What I claim and desire to secure by Letters-Patent is:—

1. A pneumatic hammer comprising a 70 main cylinder having a bore, a hammer piston arranged within said bore, an auxiliary cylinder having its interior communicating with the bore of the main cylinder and also provided with a port placing the same in 75 communication with the atmosphere, an auxiliary piston arranged within said auxiliary cylinder, and resilient means arranged within the auxiliary cylinder between one end of the auxiliary cylinder and the auxiliary 80 piston, said auxiliary piston being adapted to compress said auxiliary means during the operative stroke of the hammer piston, and said resilient means being adapted to force the auxiliary piston back to its original position on the return stroke of the hammer piston and to force air from the auxiliary cylinder into the bore of the main cylinder for assisting in returning the hammer piston to its original position. 90

2. A pneumatic hammer as claimed in claim 1 in which the auxiliary piston is provided with an extension having helical grooves, a pinion arranged coaxially with the auxiliary piston and having internal helical threads cooperating with said helical grooves, a tool arranged to be struck by said hammer piston, a toothed gear fixed to said tool and adapted to be driven by said pinion during the operative stroke of the hammer piston, and a pawl for preventing reverse motion of the pinion on the return stroke of the hammer piston. 95

3. A pneumatic hammer comprising a 105 main cylinder and an auxiliary cylinder, a conduit placing one end portion of the interior of the main cylinder in communication with one end portion of the interior of the auxiliary cylinder, a pipe for conveying pulsating air to and from one end portion of the main cylinder, a tool having a stem extending into the interior of the main cylinder, a reciprocating piston hammer arranged in the main cylinder and adapted to strike said tool, an auxiliary piston arranged in the auxiliary cylinder and adapted to be moved in one direction by air pressure passing through said conduit from the main cylinder when the piston hammer moves in one direction, and resilient means arranged in the auxiliary cylinder and bearing upon the auxiliary piston for moving the same in an opposite direction and for forcing air through said conduit into the main cylinder when the hammer piston is moved in a direction opposite to its first mentioned movement. 110

4. A pneumatic hammer as claimed in claim 3 in which a hollow cone is arranged within the main cylinder to limit the move- 115 120 125 130

ment of the piston hammer in one direction.

5. A pneumatic hammer as claimed in claim 3 having driving means arranged between the auxiliary piston and said tool for causing rotation of the tool as the auxiliary piston reciprocates.

6. A pneumatic hammer as claimed in claim 3 in which a port is provided for placing one end of the auxiliary cylinder in communication with the atmosphere. 10

Signed at Milan (Italy), this 9th day of July 1920.

ERNESTO CURTI.
